(57) **CLAIM**

The ornamental design for a device for connecting a smart/ cell phone camera to an optical device, as shown and described.

DESCRIPTION

FIG. 1 is a back perspective view of a device for connecting a smart/cell phone camera to an optical device showing my new design in an environment of use;

FIG. 2 is a back perspective view thereof;

FIG. 3 is a side elevation view thereof; and,

FIG. 4 is a front elevation view thereof.

The broken lines in the drawings depict environmental subject matter only and form no part of the claimed design.

1 Claim, 4 Drawing Sheets*FIG. 1*

FIG. 2

FIG. 3

FIG. 4
